UNITED STATES PATENT OFFICE.

CHARLES F. KETTERING, OF DAYTON, OHIO, ASSIGNOR TO DELCO-LIGHT COMPANY, OF DAYTON, OHIO, A CORPORATION OF DELAWARE.

INTERNAL-COMBUSTION ENGINE.

Original application filed April 1, 1918, Serial No. 225,902. Divided and this application filed March 6, 1920. Serial No. 363,889.

To all whom it may concern:

Be it known that I, CHARLES F. KETTERING, a citizen of the United States of America, residing at Dayton, county of Montgomery, and State of Ohio, have invented certain new and useful Improvements in Internal-Combustion Engines, of which the following is a full, clear, and exact description.

10 This invention relates to power plants including an internal-combustion engine and has for its principal object the provision of improved means in construction of the plant, and more particularly in the construction of the engine.

15 This invention is a division of the pending application, Serial Number 225,902, filed April 1st, 1918, now Patent No. 1,430,524, dated September 26, 1922.

20 The object of this invention is to provide a device for cooling the cylinder head while at the same time preheating the fuel mixture.

25 Other and further objects and advantages of the present invention will be apparent from the following description, reference being had to the accompanying drawing, wherein a preferred embodiment of one form of the present invention is clearly shown.

30 In the drawing:

Fig. 1 is a fragmentary sectional view of the upper part of an engine.

35 Referring to the drawing, 20 designates a cylinder, the lower portion being broken away, supporting a cylinder head 21 having an explosion chamber 22 provided with an inlet passage 23 and an exhaust passage 24. These passages are separated from the explosion chamber 22 by a flat partition or wall 25, which is apertured to provide ports between the chamber 22 and the passages 23 and 24. The flat partition or wall 25 serves as a seat for the intake valve 26 and exhaust 40 valve 27, which are adapted to slide in the guides 28. These valves are actuated by rocker arms 29.

45 A baffle member 30 extends across a portion of the passage 23 and deflects the incoming fuel, causing the fuel to move upwardly, as indicated by arrow 32, and strike against a partition or common wall 31 which separates the exhaust passage 24 and inlet passage 23. The partition or wall 31 being

much hotter than the incoming fuel, heat is 55 absorbed by the fuel from the partition or wall 31, thereby vaporizing the same just before its admission into the explosion chamber.

By vaporizing the fuel at a point close to 60 the combustion chamber, there is no opportunity for the fuel to condense before reaching the combustion chamber.

It is apparent from the foregoing that the present invention provides for cooling the 65 exhaust passage as well as for heating the fuel mixture. In this manner the cylinder head is prevented from becoming overheated at a point where the dissipation of heat by radiation and conduction is somewhat difficult.

70 While the form of mechanism herein shown and described constitutes a preferred embodiment of one form of the invention, it is to be understood that other forms might 75 be adopted and various changes and alterations made in the shape, size, and proportion of the elements therein without departing from the spirit and scope of the invention.

80 What I claim is as follows:

1. In a device of the class described, and in combination, an engine cylinder provided with a cylinder head, and with intake and exhaust passages within said head and communicating with said cylinder through separate ports; valves for said ports; a common wall located within said cylinder head and separating the intake and exhaust passages from one another and which wall is adapted to be heated by the exhaust gases passing through the exhaust passage; said intake passage being tortuous adjacent said common wall to thereby direct inflowing fuel against said common wall.

2. In a device of the class described, and in combination, an engine cylinder provided with a cylinder head, and with intake and exhaust passages within said head and communicating with said cylinder through separate ports; valves for said ports; a common wall located within said cylinder head and separating the intake and exhaust passages from one another and which wall is adapted to be heated by the exhaust gases passing through the exhaust passage; and a baffle arranged in and extending in a direction substantially transverse to the flow of inflowing

fuel in said intake passages, and which baffle serves to deflect the inflowing fuel against said common wall.

3. In a device of the class described, and
5 in combination, an engine cylinder provided
with a cylinder head, and with intake and
exhaust passages within said head and com-
municating with said cylinder through sepa-
rate ports; valves for said ports; a common
10 wall located within said cylinder head and
separating the intake and exhaust passages
from one another and which wall is adapted

to be heated by the exhaust gases passing
through the exhaust passage; and a baf-
fle located within said intake passage and 15
which baffle is inclined relative to the direc-
tion of flow of fuel therein, to thereby de-
flect the inflowing fuel against said common
wall.

In testimony whereof I affix my signature.
CHARLES F. KETTERING.
